WEATHER ROOF FOR FLOATING TANK ROOFS

John H. Wiggins, Chicago, Ill.

Application July 9, 1952, Serial No. 297,930

2 Claims. (Cl. 220—26)

This invention relates to a weather roof of novel construction that is adapted to be used with various kinds and types of floating tank roofs.

The main object of my invention is to provide a stationary weather roof for a liquid storage tank equipped with a floating roof, which is of such design or construction that (a) it insures sufficient ventilation for the space between the weather roof and the floating roof to make it impossible for an explosive mixture to exist in said space, and (b) it eliminates the possibility of any rain that may be blown into the space between the two roofs through a ventilating opening, from reaching the inner face of the tank side wall and eventually finding its way into the tank through the joint between the tank side wall and the peripheral sealing mechanism of the floating roof.

Figure 1 of the drawings is a vertical transverse sectional view, illustrating a floating tank roof equipped with a weather roof embodying my invention, and

Figure 2 is a top plan view of the structure shown in Figure 1.

In the drawings the reference character 1 designates the side wall of a liquid storage tank and 2 designates the bottom of the tank. Said tank is equipped with a floating roof that may be of any preferred type or design but which is herein illustrated as a modified pan type floating roof provided with a deck 3, an annular rim 4 located at the peripheral edge of said deck, and a conventional peripheral sealing mechanism that comprises an annular shoe 5 arranged in a sliding engagement with the tank side wall and a flexible gastight sealing element 5a attached to said shoe 4 and to the rim 4 of the floating roof.

My invention consists of a stationary weather roof 7 mounted on the tank and constructed and arranged so as to produce a ventilating opening A of relatively great diameter located at the center of said weather roof and an annular ventilating slot B located between the peripheral portion of said weather roof and the top edge of the side wall 1 of the tank. The weather roof 7 may be of any preferred shape or construction and it can be mounted in any preferred way on the tank side wall. It is herein illustrated as being substantially dome shape and provided at its periphery with an annular member 6 of angle shape in cross section that is rigidly attached to the tank side wall by lugs 13 of such shape and arrangement that the horizontal leg of the member 6 is maintained in spaced relation with the top edge of the tank side wall and the vertical leg of said member 6 surrounds and is maintained in spaced relation with the tank side wall, thereby producing the previously mentioned ventilating slot B between the tank side and the peripheral portion of the weather roof. The ventilating opening A at the center of the weather roof is preferably formed by an open ended tubular or cylindrical structure, mounted in the roof 7 in such a way that the major portion of the length of said structure will project downwardly a considerable distance below said roof and hence will func-

tion as a baffle that effectively prevents rain that blows downwardly through the center ventilating opening A of the weather roof from coming in contact with the inner surface of the tank side wall 1 as hereinafter described. Said tubular structure may consist of a cylinder of considerably greater diameter than length, rigidly mounted on the weather roof in such a position that its lower end is in close proximity to the floating roof when said floating roof is in its highest or uppermost position, or it may consist of a cylinder rigidly attached to the weather roof and provided with a telescoped or extensible and contractible lower end portion that folds and unfolds during the rise and fall of the floating roof.

In the form of my invention herein illustrated, the tubular or cylindrical structure that forms the center ventilating opening of the weather roof, is composed of an open ended, rigid rain and wind deflecting cylinder 9 attached to the weather roof 7 with its upper end projecting slightly above the top surface of said roof, and a collapsible cylinder 10; made of fabric, suspended from the lower end of said deflecting cylinder 9 by a supporting member 11, formed by a rod bent into circular form, and attached to lugs 14 that project inwardly from the lower end portion of the rigid cylinder 9, said supporting member 11 and lugs 14 being so constructed and arranged as to produce a ventilating slot at the lower end of the rain and wind deflecting cylinder 9 up through which air circulates as indicated by the arrow 18 at the left hand side of Figure 1. The collapsible fabric cylinder 10 has a bottom ring 12 attached to its lower end so as to impose a downward load on said fabric cylinder which tends to hold it in a distended condition in certain positions of the roof. As the floating roof rises from its lowermost position, lugs 15 on the deck 3 of the floating roof come into contact with the bottom ring 12 of the fabric cylinder 10 as shown in broken lines and thus cause said cylinder 10 to collapse or fold as shown in solid lines in Figure 1, said lugs 15 causing the bottom ring 12 of the fabric cylinder to be held in spaced relation with the deck of the floating roof and thus produce a ventilating slot through which air can enter the lower end of the collapsible fabric cylinder 10 and thence flow upwardly through same and through the rigid cylindrical member 9 at the center of the weather roof. The member 9 in addition to functioning as a rain and wind deflector, also serves as the central portion of a framework for the weather roof 7 that comprises radially disposed ribs or beams 8 attached at their inner ends to the central member 9 and attached at their outer ends to the peripheral member 6 of the roof.

In order to effectively prevent rain from being blown into the space between the floating roof and weather roof, through the annular ventilating slot B between the weather roof and the tank side wall, I prefer to attach a fabric curtain 20 to the vertical leg of the peripheral member 6 of the weather roof as shown at the right hand side of Figure 1. Said curtain 20 extends around the entire circumference of the weather roof, but it has been omitted from the left hand side of Figure 1 in order to illustrate the overflow 16 in the tank side wall that controls the maximum height to which the floating roof can rise in the tank. The curtain 20 can either be constructed in the form of a continuous annular member or it can be composed of a plurality of segmental sections that are capable of swinging relatively to each other. When wind blows hard, for example from the right hand side of the tank the curtain 20 flexes or swings into the position indicated by the dotted line in Figure 1, thereby effectively closing the peripheral venting slot B and preventing rain from being carried through said slot into the space between the floating roof and the weather roof.

The weather roof 7 covers a large portion of the total

tank area but there is a ventilating opening A of relatively great diameter at the center of the roof that insures efficient ventilation of the space between the floating roof and weather roof and also reduces the quantity of steel used in the construction of the weather roof. Even though said center ventilating opening is of relatively great diameter rain that blows downwardly through same will not come in contact with the inner surface of the tank side wall and eventually find its way into the liquid storage space of the tank, due to the fact that said center ventilating opening is formed by a tubular or cylindrical structure that functions as follows: (a) It causes wind blowing over the top side of the roof 7 in the direction indicated by the arrow 17, to create a partial vacuum over the windward half of the opening A, and (b) it directs the wind that hits the leeward side of the cylinder 9 downwardly as indicated by the arrows 19 in Figure 1, thereby causing any rain drops carried by such wind to be deflected downwardly in substantially a straight line as shown in Figure 1. If the tank side wall is relatively low compared to its diameter, a cylindrical, rigid member 9 mounted in the central portion of the weather roof 7 will deflect downwardly any wind currents that blow downwardly through the center ventilating opening A, but if the tank side wall is very high compared to its diameter it is necessary to equip the weather roof with a central wind and air deflector provided with a collapsible or telescoping lower end portion 10 so as to increase the deflecting effect of the tubular or cylindrical member 9 mounted in the roof, said members 9 and 10 being preferably of such construction that there is a ventilating slot or space between said members at the point where they are joined together and also between the lower end of the member 10 and the deck of the floating roof as previously explained.

In order to prevent rain from being blown inwardly through the ventilating slot B between the weather roof and the tank side wall under high wind conditions, I prefer to attach a flexible or swinging curtain or rain shield 20 to the peripheral portion of the weather roof as previously explained. When a hard wind is blowing from the right (looking at Figure 1) the shield 20 will flex or swing into the dotted line position so as to close the ventilating slot B on the windward side and prevent rain from blowing inwardly through said slot.

With a proper peripheral seal on the floating roof and for liquids that do not boil at the temperature to which they are subjected during storage, a weather roof constructed in accordance with my invention provides more than ample circulation of air between the floating roof and the weather roof, without liability of rain, even a driving rain, coming in contact with the tank side wall and eventually finding its way into the tank by leaking through the sealing mechanism at the periphery of the floating roof which acts on the inner face of the tank side wall. Also as previously explained by equipping the weather roof with a centrally located, open ended tubular structure of relatively great diameter that effectively

ventilates the space between the weather roof and floating roof without liability of the liquid stored in the tank becoming contaminated by rain water, I reduce the quantity of steel used in the weather roof and hence reduce the cost of same.

Having thus described my invention, what I claim and desire to secure by Letters Patent is:

1. The combination of a liquid storage tank provided with a cylindrical side wall, a floating roof in said tank, 10 a stationary weather roof of greater diameter than said tank mounted on the upper end of same with the under side of said weather roof spaced away from the top edge of the tank side wall so as to form an annular ventilating slot that extends around the entire circumference of the tank, a depending flange on the periphery of said weather roof extending downwardly from same to a point below the top edge of the tank side wall and spaced away from same so as to form a baffle that prevents rain from blowing inwardly through said annular ventilating slot, a stationary, vertically disposed open ended tubular member of relatively great diameter mounted in said weather roof with the lower end of said tubular member terminating at a point a substantial distance below the under side of said weather roof, and a contractile and extensible tubular structure suspended from the lower end of said stationary tubular member so as to form an extension of same that is adapted to be engaged by the floating roof when the liquid in the tank is above a certain approximate level, the upper end of said contractile and extensible structure being spaced away from the lower end of said stationary tubular member and disposed in telescoped relationship with same so as to form an annular ventilating slot for the space between the floating roof and stationary roof when said extension is in engagement with the floating roof.
2. A structure of the kind described in claim 1, which also includes a means carried by the peripheral flange of the stationary roof for preventing rain from blowing inwardly through the annular ventilating slot between said roof and the tank side wall, and a means for producing a ventilating opening between the floating roof and the lower end of the extension of the tubular member on the stationary roof when said extension is in engagement with the floating roof.
